UNITED STATES PATENT OFFICE

GORDON E. ROEDDING, OF GRAND RAPIDS, MICHIGAN, ASSIGNOR TO GRAND RAPIDS
BRASS COMPANY, OF GRAND RAPIDS, MICHIGAN

LATCH

Application filed July 13, 1929. Serial No. 377,990.

The main object of this invention is to provide an automatically engaging latch for refrigerator doors and the like which has few parts, these parts being economical to produce and assemble, and at the same time strong and durable.

A further object is to provide a latch of this type with a so-called "drop" or depending handle or actuating lever.

Objects relating to details and economies of my invention will appear from the description to follow. The invention is defined and pointed out in the claims.

A structure which is a preferred embodiment of my invention is illustrated in the accompanying drawing, in which:

Fig. 1 is a fragmentary elevation of a door and its casing with one of my improved latches mounted thereon, the latch housing and actuating lever being shown in section on line 1—1 of Fig. 3.

Fig. 2 is a fragmentary view looking from the left of Fig. 1.

Fig. 3 is a fragmentary section on line 3—3 of Figs. 1 and 4.

Fig. 4 is a fragmentary section on line 4—4 of Figs. 1, 3 and 5.

Fig. 5 is a plan view of the housing back or base plate with the bolt actuating spring mounted thereon.

Fig. 6 is a sectional view of the back plate showing structural details thereof.

In the accompanying drawing, 1 represents a door and 2 its casing. The latch housing 3 is provided with a back plate 4 having a tubular pivot or bearing member 5 struck up therefrom. This latch housing may be effectively formed as a stamping.

The back plate is formed with a curved slot 6 extending from one side of the pivot 5 and a radial slot 7 on the opposite side, the purpose of which will appear later.

The bolt 8 is also formed as a stamping and is provided with a pivot engaging or bearing portion 9 which engages the pivot member for swinging and longitudinal tilting movement.

The back plate is provided with bolt detent slots 10 while the bolt is provided with detent

lugs 11 adapted to engage the said slots when the bolt is swung to retracted position.

A coiled spring 12 is arranged in the pivot member 5 and is provided with a U-shaped arm 13 at its lower end engaged in the curved or U-shaped slot 6 of the back plate, the end of the arm engaging the slot 7. The spring terminates in a radial arm 14 at its upper end which is engaged with the lugs 15 struck downwardly from the bolt, these lugs being arranged in opposed spaced relation. The engagement of the spring with the back plate is such as to support it not only against rotative movement but also against longitudinal movement. The spring is engaged with the bolt under tension so that it tends to urge the outer end of the bolt toward the back plate and also to yieldingly hold the bolt against its stop 16, the edge of the opening 17 through which the bolt projects constituting a stop.

The bolt is swung to retracted position by means of the lever 18 which is pivoted at 19 on the housing and provided with a forked arm 20 projecting into the housing to engage the spherically curved end 21 on the bolt. When the bolt is swung to its retracted position by this lever, the spring rocks the bolt longitudinally bringing its detents into engagement with the bolt detent slots 10. The coacting keeper 22 is provided with a trap or tappet 23 with which the bolt engages as the door is swung to its closed position, thereby lifting the detents 11 from the slots 10, allowing the spring to actuate the bolt.

My improved latch has few parts. These parts may be very economically produced and assembled. The structure is compact and at the same time very strong.

I have illustrated and described my improvements as adapted for refrigerator doors. I have not attempted to illustrate or describe other modifications or adaptations as it is believed this disclosure will enable those skilled in the art to embody or adapt the same as may be desired.

Having thus described my invention, what I claim as new and desire to secure by Letters Patent, is:

1. In a latch, the combination of a housing provided with a back plate having a tubular

- pivot member projecting therefrom, a curved slot at one side of said pivot member and a radial slot at the opposite side, said back plate also having a bolt detent slot, a bolt 5 provided with actuating means and mounted on said pivot member for swinging and tilting movement and provided with a detent lug engageable with said detent slot, said bolt also having spaced oppositely disposed 10 lugs struck inwardly therefrom and positioned above said pivot member, and a coiled spring arranged in said pivot member and terminating in a U-shaped arm engaged in said slots in said back plate whereby the 15 spring is supported against rotative and longitudinal movement, said spring terminating at its upper end in a radially disposed arm engaged with said lugs on said bolt under tension whereby the spring acts to urge said 20 bolt to latching position and said detent into engagement with said detent slot.
2. In a latch, the combination of a housing having a back plate provided with a tubular pivot member and with a bolt detent, a 25 bolt mounted on said pivot member for swinging and tilting movement and having a spherically curved bearing portion at its inner end, a coiled spring arranged in said pivot member and terminating at its lower 30 end in an arm engaged with said back plate for supporting the spring against rotative and longitudinal movement, said spring terminating in an arm at its upper end engaged with said bolt so that the spring acts to urge 35 the bolt to latching position and into engagement with said dentent, and a lever pivotally mounted on said housing and having a forked arm engaging the spherically curved bearing portion on said bolt.
- 40 3. In a latch, the combination of a housing having a back plate provided with a tubular pivot member and with a bolt detent, a bolt mounted on said pivot member for swinging and tilting movement, a coiled spring arranged in said pivot member and terminating at its lower end in an arm engaged with said back plate for supporting the spring against 45 rotative and longitudinal movement, said spring terminating in an arm at its upper end engaged with said bolt so that the spring acts to urge the bolt to latching position and into engagement with said detent, and means for retracting said bolt and disengaging it from said detent.
- 50 4. In a latch, the combination of a housing provided with a bolt detent, a bolt mounted in said housing for swinging and tilting movement, a coiled spring disposed concentrically relative to the bolt pivot and connected at one end to said housing and at the other to said bolt whereby the bolt is urged to latching position and also into engagement with said detent, and a lever mounted 55 on said housing and operatively connected

to said bolt to swing the bolt to detent engaging position.

5. In a latch, the combination of a housing provided with a bolt detent, a bolt mounted for swinging and tilting movement and having a spherically curved bearing portion at its inner end, a spring acting to urge the bolt to latching position and into engagement with its said detent, and a lever pivotally mounted on said housing and having a forked arm engaging the spherically curved bearing portion on said bolt.

In witness whereof I have hereunto set my hand.

GORDON E. ROEDDING.
